[57] CLAIM

The ornamental design for a glass fireplace door, as shown and described.

DESCRIPTION

FIG. 1 is a front elevational view of a glass fireplace door, showing our new design;

FIG. 2 is a rear elevational view thereof;

FIG. 3 is a top plan view thereof;

FIG. 4 is a side elevational view thereof;

FIG. 5 is an enlarged fragmentary side elevational view taken at line 5—5 of FIG. 1;

FIG. 6 is a front perspective view thereof.
